UNITED STATES PATENT OFFICE.

CARLOS M. WHITAKER, OF GHENT, KENTUCKY.

GATE-OPERATING MECHANISM.

Application filed May 28, 1926. Serial No. 112,384.

This invention relates to gate operating mechanisms and more particularly to a device of this character for operating a vertically swinging pivoted gate.

5 An important object of the invention is to provide a device of this character which may be very cheaply and readily constructed and at the same time be durable and efficient in service.

10 A further object of the invention is to provide a device of this character whereby two shifting elements, one arranged at each side of the gate upon the right-of-way passing through the gate, serve to completely 15 control the opening and closing movements of the gate without regard to the direction of travel of the vehicle approaching the gate.

A still further object of the invention is 20 to provide novel and improved means for counterbalancing the gate in its pivotal movement.

A further object of the invention is to 25 provide an operating mechanism including two control elements which are arranged at opposite sides of the gate in which connections are provided between the control elements whereby engagement of one of the control elements in a given direction opens 30 the gate, at the same time shifting the other control element to a position where the vehicle continuing its travel and engaging the control element to operate the same in the same direction in which the first control element was operated, closes the gate and 35 resets the control elements for a further operation.

These and other objects I attain by the 40 construction shown in the accompanying drawings, wherein for the purpose of illustration is shown a preferred embodiment of my invention and wherein:—

Figure 1 is a plan view showing a gate operating mechanism therefor constructed 45 in accordance with my invention, the gate being shown in the closed position in solid lines and in the open position in dotted lines;

Figure 2 is an enlarged side elevation of 50 the gate showing the same in solid lines in the closed position and dotted lines in the open position;

Figure 3 is an enlarged view of the operating mechanism for the gate;

55 Figure 4 is a side elevation of the operating mechanism for the gate;

Figure 5 is a section on the line 5—5 of Figure 4;

Figure 6 is a section on the line 6—6 of 60 Figure 4;

Figure 7 is a front elevation of one of the operating elements for the gate.

Figure 8 is an enlarged view of one of the reciprocating bars for the gate.

Referring now more particularly to the drawings, the numeral 10 indicates a base plate which is adapted to be placed at one side of a right-of-way R and when employed with a vertically swinging gate to be positioned to extend transversely of the right-of-way. This base plate has, intermediate its ends, at the sides thereof standards 11 mounting a pivot 12 for the gate 13, the connections of the gate with the pivot being such that the bottom face of the gate, when in either horizontal or vertical position, is spaced above the upper surface of the base plate. Threaded into the plate at opposite ends thereof and adjacent each side of the plate are pairs of pivots 14 upon which are mounted rollers 15 so constructed that between the rollers of each pair in a direction extending transversely of the plate and longitudinally of the right-of-way a slot 16 is formed, for a purpose presently 75 to appear.

The rollers are maintained in position upon the pivots thereof by flanges 17 formed upon the ends of the arms of a U-shaped yoke member 18, these flanges being secured 80 to the heads of the pivot elements by nuts 19 or the like. Between the arms of each U-shaped yoke extends a horizontal pivot 20 upon which is mounted a further roller 21.

A strap 22 is passed between the upper surface of the base plate and the rollers and has its ends secured to one end 23 and the bottom 24 of the gate at points spaced from the pivot 12 which is arranged at the connection between said end and the bottom. Mounted in the slots between the rollers 15 at one end of the base plate is a bar 25, while a similar bar 26 is correspondingly mounted in the slots of the rollers at the opposite ends of the base plate. These bars 105 extend longitudinally of the right-of-way and each have secured thereto one end of a strap 27 passed about the inner rollers at one side of the plate and one end of a second similar strap 28 passed about the inner rollers of the pairs at the opposite sides of the plate. It will be noted that if the bar

26 is shifted longitudinally in the direction of the arrow A in Figure 3, the strap 27 will exercise a longitudinal pull upon the bar 25, causing the bar 25 to move in the direction of the arrow B of this figure, while a corresponding but reverse movement takes place if the bar 25 is shifted in a direction opposite to the direction of the arrow B. If the bar 25 is initially shifted in the direction of the arrow B, then the strap 28 exercises a pull upon the bar 26, causing it to move in the direction of the arrow A and subsequent movement of the bar 26 in a direction opposite to the direction of the arrow A causes a corresponding but reverse movement of the bar 26, again instigated by the strap 28. Thus, at each operation, one of the straps serves to provide transfer operation of one bar to another and the other of the straps 20 acts as an idler and the strap which acts to provide the shifting depends upon which of the bars is primarily actuated. To one of the straps 27 or 28 is secured the vertical flange 29 of an angle plate, the horizontal flange 30 of which is secured to the strap 22. This horizontal flange is preferably provided in its under surface with downwardly extending guide flanges 31 and 32 adapted to engage with opposite side faces 30 of a longitudinally extending guide strip 33 secured to the upper surface of the base plate.

Arranged at opposite sides of the gate 13 and suitable distances from the gate are pivots 34 for shafts 35 directed transversely of the right-of-way and each having at opposite ends thereof cranks 36 and 37, the crank 37 being provided with a roller. The cranks 37 and 36 are counterbalanced, as at 38, so that they are normally vertically disposed and extend upwardly from the shaft. To each crank 36 is secured one end of a link 39, the opposite end of which is engaged in a slot 40 formed in the coacting bar 25 or 26. When the gate is horizontally disposed, the connection between the link 39 and the corresponding bars 25 or 26 is arranged at the inner end of the slot, or that end next adjacent to the base plate 19, with the result that if one of the cranks 37 is engaged by the wheel of a vehicle and shifted toward the base plate, the link 39 and bar associated therewith operate as a solid unit. Since, however, the second bar operates reversely to the first actuated bar, the second crank 37 is unaffected, the associated bar merely moving, so that the link connection 40 shifts from one end to the opposite end of the slot. The shifting of the bar exercises a pull upon the straps 27 and 28 which is transferred to the strap 22, causing the gate to open. The vehicle passing through the gate engages the second crank which now has its pivotal connection 40 arranged at the end of the slot remote from the gate, with the result

that when the vehicle engages with the second crank, the second bar is operated, causing the gate to again swing about its pivots and shift to the closed position. When the gate closes, the counterbalance of the second crank will return the crank to vertical position and accordingly shift the link 39, so that it is again disposed in the normal position or with its pivot at the inner end of the slot. The shifting action of the bars 25 caused by the engagement with the second crank has already shifted the bar which was initially operated, so that its link pivot is correspondingly arranged.

Pivoted to the end 23 of the gate between the point of connection of the strap 22 therewith and the pivot 12 is an arm 41 having a roller 42 engaging the strap 22 adjacent its inner end and adjacent its outer end an adjustably secured counterweight 43. Adjacent its outer end, this arm has secured thereto one end of a flexible element 44, the opposite end of which is connected with the top of the gate adjacent the end 23. The arm preferably projects from the gate at an angle of 45° to the end 23, so that while the gate is moving from a vertical to a horizontal position and when the center of gravity of the gate passes a vertical plane including the pivot of the gate, the weight 43 which is previously supported from the ground is lifted from the ground and counterbalances the further movement of the gate. As the gate is moving from a horizontal to a vertical position and the center of gravity of the gate passes the pivot, the arm 41 comes in contact with a roller pivot 45 properly positioned upon the ground adjacent the end 23 of the gate, with the result that the outer end of this arm during continued movement of the gate to the vertical position moves upwardly instead of downwardly, again applying the resistance of weight 43 to the settling movement of the gate. Thus, the weight 43 serves to check the movement of the gate during its movement to both horizontal and vertical positions and, it will, of course, be obvious that this weight will also reduce the resistance to movement of the gate to a point where this resistance may be readily overcome by engagement of a vehicle wheel with a crank 37.

A gate for this purpose should be very lightly and at the same time strongly constructed. To this end I preferably form the gate with a rectangular frame 46 of planks of considerable width, but of reduced thickness. To the inner faces of these planks, I bolt bracing strips 47 which serve not only as a means for bracing the frame 46 but likewise as a means for attaching a wire or similar covering 48. Adjacent the center of the frame, I provide a vertically extending brace 49 from the upper end of which to

the lower corner of the free end of the frame a diagonal brace 50 extends. At the corner receiving the pivot 12, bracing plates 51 are preferably installed through which the pivot 5 is directed. Such a gate will be light and, therefore, readily actuated and at the same time will be sufficiently rigid to withstand the jars to which a gate of this character is necessarily subjected.

10 Since the construction hereinbefore set forth is obviously capable of a certain range of change and modification without materially departing from the spirit of the invention, I do not limit myself to such specific 15 structure except as hereinafter claimed.

I claim:—

1. In combination with a gate pivoted to swing from a closed position where it is horizontal to an open position where it is 20 vertical, a pair of parallel bars spaced longitudinally of the gate and extending transversely thereof, said bars being arranged at opposite sides of the pivot of the gate, a web secured to the gate at opposite sides of 25 the pivot thereof and passing about guides arranged at opposite sides of the pivot of the gate in a direction longitudinal of the gate and a connection between the bars whereby 30 movement of either the bars causes a corresponding movement of the other bar in the reverse direction, including a member paralleling the web and shifting longitudinally at that portion thereof paralleling the web as the bars are shifted and a connection 35 between the web and member.

2. In gate operating mechanism and in combination with a gate pivoted to swing from a position obstructing a right-of-way to a position at one side of the right-of-way, 40 a pair of parallel bars, a connection between the bars whereby the bars move in opposite directions when either of the bars is actuated, an operative connection between the bars and the gate whereby the gate is rotated to open or close the same when the bars are shifted, a pair of crank shafts arranged at opposite sides of the gate and each having a crank for engagement by the vehicle and a second crank link-connected with 45 one of said bars, the link connection having a lost motion engagement with the associated bar and being operable to shift the bar when the associated crank is engaged by a vehicle approaching the gate only when the gate is 50 in the closed position and by a vehicle receding from the gate only when the gate is in the open position, two pairs of rollers each including a roller arranged adjacent one of said bars, a web passed about each pair 55 of rollers and having opposite ends thereof 60

secured to said bars, and an operative connection between one of said webs and the gate.

3. In a gate operating mechanism and in combination, an elongated base plate extending transversely of the right-of-way, a horizontal pivot carried by the base plate centrally thereof, a gate mounted upon the pivot to swing from horizontal to vertical positions, a web secured at one end to the 65 bottom of the gate and at its opposite end to the back of the gate at points spaced from said pivot, a pair of horizontally disposed guide rollers mounted upon said base plate adjacent opposite ends thereof and about 70 which said web is passed, two pairs of vertically disposed guide rollers each including a roller arranged adjacent a guide roller of the first mentioned pair, bars operating adjacent corresponding guide rollers of the 75 last named pairs, a web passed about each of the last named pairs of guide rollers and secured at its ends to said bars, a connection between one of said webs and the web secured to the gate and means engaged with 80 said bars for shifting the bars longitudinally.

4. In a gate operating mechanism and in combination, an elongated base plate extending transversely of the right-of-way, a horizontal pivot carried by the base plate 90 centrally thereof, a gate mounted upon the pivot to swing from horizontal to vertical positions, a web secured at one end to the bottom of the gate and at its opposite end to the back of the gate at points spaced from 95 said pivot, a pair of horizontally disposed guide rollers mounted upon said base plate adjacent opposite ends thereof and about which said web is passed, two pairs of vertically disposed guide rollers each including 100 a roller arranged adjacent a guide roller of the first mentioned pair, bars operating adjacent corresponding guide rollers of the last named pairs, a web passed about each of the last named pairs of guide rollers and 105 secured at its ends to said bars, a connection between one of said webs and the web secured to the gate, means engaged with said bars for shifting the bars longitudinally including a crank shaft for each bar having 110 a crank for engagement by a vehicle and a second crank to which a link is pivoted, the opposite end of the link having a pin and slot engagement with the associated bar, the crank being biased to maintain the same 115 in vertical position.

In testimony whereof I hereunto affix my signature.

CARLOS M. WHITAKER.
